DESIGN FOR A FIRE-PLACE.

Design No. 13,451, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,451, dated November 21, 1882.

Application filed October 17, 1882. Term of patent 7 years.

To all whom it may concern:

Be it known that I, WILLIAM C. PEET, of Jersey City, in the State of New Jersey, have invented a certain new and ornamental Design for Fire-Places, of which the following is a specification.

The design of this fire-place is for producing a particular artistic effect, as shown in the accompanying engraving. The fire-place frame is recessed, the side pieces being at an angle to each other and to the top frame. The border *a* of the frame is molded, and the surfaces of the side pieces are ornamented with urns at *b*, scroll, leaflet, and rosette designs at *c d*. The upper portions are divided horizontally and vertically by bars, and the panels contain scroll, leaflet, and flower ornaments, as at *e f g*, as represented in the engraving. There is a hood extending out over the grate, having an ornamental border, *k*, and scroll, leaflet, and flower ornaments in panels, as at *l*, as shown. The fender has urn *m* at the angles, with bases *n*, ornamented as represented. The upper part of the fender has an astragal border, *o*, and the front of the fender is ornamented with scroll, leaflet, and griffin designs *p q* in relief in the panels, and a central circular ornament, *r*. The wings of the fender have square rosette-bases *s*, feet *t*, arch *u*, and astragal border *o*, forming a base for the greyhound figures *v*, substantially as shown. The fire-place has fluted hobs *w*, urns 2, rails 3, and balustrade ornaments 4. The back of the fire-place is ornamented with knobs 5 and leaflet radiate designs, as shown. The sides and back

of the fire-place inclosure are ornamented with pansy designs in diamond panels, as represented at *x*.

I claim as my invention—

1. The design of the shape and configuration of the fire-place frame, consisting of the inclined side pieces and the hood, substantially as shown. 40

2. The ornamental designs for the surface of the fire-place frame, consisting of the urns, scroll, leaflet, and flower ornaments, substantially as represented. 45

3. The design of the hood, consisting of the ornamental border *k*, and the scroll, leaflet, and flower ornaments, as shown. 50

4. The design of the fender, consisting of the urns *m*, bases *n*, leaflet, scroll, and griffin ornaments *p q*, and border *o*, substantially as represented. 55

5. The design of the wings of the fender, consisting of the bases *s*, feet *t*, arch *u*, and greyhound figure *v*, substantially as represented. 60

6. The design of the fire-place, consisting of the fluted hobs *w*, urns 2, and balustrade ornaments, substantially as set forth. 65

7. The design of the pansy and diamond-surface ornaments on the sides and back, as represented.

Signed by me this 13th day of October, A. D. 1882.

WILLIAM C. PEET.

Witnesses:

WILLIAM G. MOTT,
GEO. T. PINCKNEY.
